UNITED STATES PATENT OFFICE

CONRAD C. DAHL, OF DETROIT, MICHIGAN, ASSIGNOR TO BURROUGHS ADDING MACHINE COMPANY, OF DETROIT, MICHIGAN, A CORPORATION OF MICHIGAN

DESIGN FOR A TYPEWRITER

Application filed September 18, 1931. Serial No. 41,140. Term of patent 14 years.

To all whom it may concern:

Be it known that I, CONRAD C. DAHL, a citizen of the United States, residing at Detroit, county of Wayne, State of Michigan, have invented a new, original, and ornamental Design for Typewriter, of which the following is a specification, reference being had to the accompanying drawing, forming a part hereof, wherein the figure is a perspective view of a typewriter, showing my new design.

I claim:

The ornamental design for a typewriter, as shown.

CONRAD C. DAHL.
